United States Patent Office

Des. 204,650
Patented May 3, 1966

204,650

TOASTER

John E. Reed, Glen Ellyn, Ill., assignor to Sunbeam Corporation, Chicago, Ill., a corporation of Illinois

Filed July 8, 1965, Ser. No. 86,090

Term of patent 14 years

(Cl. D81—10)

Fig. 1.

Fig. 2.

FIG. 1 is a perspective view of a toaster, showing my new design;

FIG. 2 is a top plan view thereof;

FIG. 3 is a side elevational view thereof;

FIG. 4 is an end elevational view thereof; and

FIG. 5 is a fragmentary sectional view taken along line 5-5 of FIG. 4.

The dominant features of my design reside in the portions shown in full lines.

I claim:

The ornamental design for a toaster, as shown and described.
